UNITED STATES PATENT OFFICE.

CHARLES R. KITTLE, OF MONROVIA, CALIFORNIA, ASSIGNOR TO ARTHUR E. OVER BURY, OF MONROVIA, CALIFORNIA.

FRAMING MACHINE.

Application filed November 24, 1926. Serial No. 150,544.

My invention relates to a machine to be used by carpenters in framing and finishing wooden buildings and the object thereof is to provide a machine by means of which a 5 number of different results can be accomplished in a single machine which heretofore required several machines to accomplish.

Fig. 1 is a side elevation.

Fig. 2 is a rear end elevation.

10 Fig. 3 is a top plan.

Fig. 4 is a front end elevation.

Figs. 5 to 9 are detail views of various parts.

In the drawings the outer and stationary 15 frame is composed of the vertical members 15 and the cross members 16 which are suitably cross braced to the vertical members. In the outer frame is the inner frame which during certain operations reciprocates in the 20 outer frame. The inner frame is composed of a bottom member 17 and a top member 19 which are connected at one side by the vertical member 17a. At the other side 17 is secured to a bottom pedestal 18. At the other 25 side 19 is secured to a top pedestal 20. A frame composed of bottom members 72 and top members 73 and vertical members 74 is connected to pedestals 18 and 20 and I term this last frame the power frame. The top 30 and bottom members of the inner frame are suitably supported on rollers attached to the outer frame. In the drawings, I have shown the motive power as an electric motor and will describe it as an electric driven machine 35 but in place of the motor I could use a small gas engine. In the power frame is suitably mounted the driving motor 21 which is supplied with a current from a source of electricity not shown. On the motor shaft 22 is 40 mounted a pinion 23 which meshes with a gear 24 mounted on shaft 25. Shaft 25 is mounted in bearings secured to the power frame and outside the bearings has mounted thereon the lower band saw wheel 26.

45 Adjustably mounted on the upper pedestal is an arm 27 which may be vertically adjusted thereon and is also revolvable thereon. Arm 27 carries a set screw 28 by means of which the position of the arm on the pedestal 50 is fixed. Arm 27 carries a forwardly projecting top lug 29 and a bottom lug 33 through which pass bolts 30 which bolts also pass through a U-shaped bearing block 34 which is engaged by an adjusting screw 32 which is 55 revolvable but not longitudinally movable in

lugs 29 and 33. Screw 32 passes through bearing block 34 in threaded contact therewith whereby block 34 may be adjusted up or down. Block 34 carries a shaft 35 on which is revolvably mounted the upper band 60 saw wheel 36.

On the rear end of shaft 25 is a worm 37 which engages gear 38 on shaft 39. Shaft 39 has splined thereon the lower member 40 of a clutch of the Ford type. The upper member 41 of the clutch is mounted on a sleeve 71 on shaft 39. Sleeve 71 carries a crank 42 which is adjustably connected to a connecting bar 43. Bar 43 is pivoted to the saw table frame 59 and when the clutch members are engaged the power frame is caused to reciprocate and carry the inner frame back and forth. A clutch lever 45 is mounted on the power frame and when the outer end is engaged by the detent lever 46 the clutch 70 members are engaged. Upon the movement of the power frame to the rear lever 46 engages a cross bar 47 of the outer frame which causes it to disengage from lever 45, thereby permitting member 40 to drop and the clutch 75 members to separate and the reciprocation of the power frame stops. A jointed lever 48 runs to the front of the outer frame and raises lever 45 so as to cause it to engage 46 and thereby cause 40 to engage 41 and when desired can be locked so as to hold lever 45 80 keeping 40 in engagement with 41 so that the reciprocation of the power frame continues. Arm 27 has slidably mounted thereon a shaft 49 which is held positioned therein by set 85 screw 50. Shaft 49 has adjustably secured thereto a depending shaft 75 which carries the upper band saw guide composed of head block 51 and rollers 52 and 53 between which rollers band saw 54 travels when the 90 machine is operated for using the band saw.

Mounted on the power frame is a shaft 55 which carries the lower band saw guide composed of head block 56 which has mounted thereon rollers 57 and 58 between which rollers band saw travels when the machine is 100 operated for using the band saw. A saw table 59 is secured to the outer frame and has suitable slots therein to accommodate the movement of saw 54. One slot 60 is longitudinal of the outer frame and is the one principally used. As shown in the drawings, I prefer to mount the band saw wheels so that the plane that passes across the faces thereof shall be angular to slot 60 and to so guide 105 110

saw 54 that it will pass through the center longitudinal line of slot 60 when sawing. Slot 60 is the band saw slot.

To the front of the outer frame I connect 5 a swinging and hingedly formed auxiliary tool frame 61 which has mounted therein tool shaft 62. Shaft 62 may have mounted thereon a rip saw 63. Shaft 62 also has mounted thereon a pulley 66 around which a 10 rope belt 67 passes. Belt 67 also passes around idler pulleys 68 on the outer frame and around pulley 69 on shaft 22.

When frame 61 is swung up to operative 15 position, saw 63 would project through a slot 70 in the saw table and belt 67 would be taut enough to drive shaft 62. When frame 61 is swung down into its inoperative position belt 67 would be too loose to drive shaft 62. Slot 70 is the rip saw slot.

20 By this construction it will be seen that I have provided a framing machine that will enable workmen to perform with one machine what is usually done by several machines, as with the band saw I can cut off all timbers 25 used in ordinary house construction and can notch rafters. I can cut coarse scroll work and I can rip strips up to a width of inches. By having the inner frame which carries the 30 saws reciprocate there is no danger of the saws becoming bound in the work and breaking and the ends of long timbers can be cut off by one workman as he can block up the longer end; whereas if the timber was fed to the saw it would require two men to handle 35 it while the end was being sawed off.

Having described my invention I claim:

1. In a framing machine, an outer frame; guiding means mounted upon said frame; a saw table mounted upon said frame, said 40 table having a band saw slot therein; an inner frame adapted to reciprocate in said outer frame on said guiding means; a band saw mounted on said inner frame angularly to the plane of movement of the frame and having one side thereof passing through the band saw slot in the saw table; means carried by said inner frame to flex said saw to cause it to pass centrally through the saw table slot and to adapt it to move in said slot; a power 45 frame mounted on said inner frame; power mechanism mounted on said power frame;

and connecting means between said power mechanism and said saw, whereby when said power mechanism is operating said saw is operated.

55

2. The invention according to claim 1 and means connected to said outer frame and to said power mechanism whereby when said power mechanism is operating said saw is operated and said inner frame is reciprocated.

60

3. In a framing machine, an outer frame; an inner frame mounted in the outer frame to reciprocate therein; power mechanism carried by said inner frame; a shaft mounted in said inner frame and operatively connected to said power mechanism; a clutch on said shaft composed of a lower member splined to said shaft and movable thereon and an upper member revoluble on said shaft when disconnected from the lower member; means 65 to connect said upper member to said outer frame, whereby when said shaft is revolved and said clutch members are engaged said inner frame is caused to reciprocate.

70

4. The invention according to claim 3; and means to cause the disengagement of said clutch members at each reciprocation of the inner frame.

75

5. In a framing machine, an outer frame; an inner frame mounted in the outer frame to reciprocate therein; power mechanism carried by said inner frame; a shaft mounted in said inner frame and operatively connected to said power mechanism; a clutch on said shaft composed of a lower member splined to said shaft and movable thereon and an upper member revoluble on said shaft when disconnected from the lower member; means 80 to connect said upper member to said outer frame, whereby when said shaft is revolved and said clutch members are engaged said inner frame is caused to reciprocate; means to cause the disengagement of said clutch members at each reciprocation of the inner frame; and means to render ineffectual the clutch 85 members disengaging means at the will of the operator.

90

In witness that I claim the foregoing I have hereunto subscribed my name this 2nd day of October, 1926.

CHARLES R. KITTLE.
